CLAIM

The ornamental design for a shoe, as shown and described.

DESCRIPTION

FIG. 1 is a top, left, and front perspective view of an ornamental design for a shoe; and,

FIG. 2 is a left elevational view of the shoe of FIG. 1. The dash-dash-dash broken lines are included for the purpose of illustrating portions of the shoe that form no part of the claimed design. The dash-dot-dash broken lines are included for the purpose of illustrating a boundary line and form no part of the claimed design.
